Western Electric Company, Incorporated, New York, N. Y., a corporation of New York

Application May 10, 1934, Serial No. 51,736

Term of patent 14 years

To all whom it may concern:

Be it known that I, ALBERT L. SINCLAIR, a citizen of the United States, residing at Hinsdale, in the county of Du Page and State of Illinois, have invented a new, original, and ornamental Design for a Table, of which the following is a specification, reference being had to the accompanying drawing, forming part thereof.

The figure is a perspective view of a table, showing my new design.

I claim:

The ornamental design for a table as shown.
In witness whereof, I hereunto subscribe my name this 26th day of April 1934.

ALBERT L. SINCLAIR.
